UNITED STATES PATENT OFFICE.

WALTER VAN BRAAM ROBERTS, OF PRINCETON, NEW JERSEY.

LOUD-SPEAKING TELEPHONE RECEIVER.

Application filed May 16, 1922. Serial No. 561,331.

To all whom it may concern:

Be it known that I, WALTER VAN BRAAM ROBERTS, a citizen of the United States, and a resident of Princeton, in the county of 5 Mercer and State of New Jersey, have invented a new and Improved Loud-Speaking Telephone Receiver, of which the following is a full, clear, and exact description.

This invention relates to loud speaking 10 receivers, and has particular reference to one in which the vibration of a plurality of diaphragms is more efficiently adapted for use in connection with loud speaking telephone receivers.

15 An object of the invention is to increase the magnification of amplitude of a loud-speaking device and eliminate any necessity for the use of fixed pivots, which are one of the causes of unnecessary friction.

20 Another object resides in the provision of means whereby the volume of sound is increased from a given available amount of power by reason of the elimination of friction in the various parts.

25 A further object resides in the particular construction and arrangement of parts which are hereinafter described and claimed and shown in the accompanying drawings.

The invention is illustrated in the drawings, of which—

30 Figure 1 is an elevation of certain parts in section of one form of the device.

Figure 2 is a side elevation of the magnets and the armature.

35 The form of the invention shown in the drawings is a preferred form, although it is understood that modifications in the construction and arrangement of the parts and in the character of the materials used may 40 be adapted without departing from the spirit of the invention.

In the commonest type of telephone receiver a vibratory diaphragm is driven directly by an electromagnet. It is well known 45 that the efficiency of transformation of electrical energy to sound energy may be improved if the electromagnet is employed to drive an armature which forms part of one end of a lever of proper design, working on 50 a pivot, and attached at the other end to a vibratory diaphragm, which in this case need not be of magnetic material. Thus a small amplitude of motion of the armature may be and has been translated into a larger 55 amplitude of motion of the diaphragm, resulting in an increased acoustic output.

One of the objections, however, to this method of connecting up the motion of the armature is the mechanical friction at the fixed pivot of the lever. My invention aims to 60 eliminate this friction by eliminating the necessity for the use of a fixed pivot. The main feature of the invention whereby I eliminate this friction resides in the fact that I use two diaphragms, one connected at 65 each end of the lever system of which a vibrating armature forms a part. By this means an increased volume of sound is obtained with the same available amount of electrical power. This is in addition to the 70 increase in efficiency resulting from the elimination of the pivot.

This invention may, of course, be embodied in many forms, of which one of the preferred forms is shown in the drawings, 75 and comprises two fixed horseshoe magnets in which the poles are represented as N, S and N', S'. These magnets may be of the permanent type or they may be electrically energized by any special direct current (not 80 shown). 1 is a fixed coil which is adapted preferably, to be energized by any suitable varying electrical current which is to be reproduced as sound. The coil 1 is designed to magnetize a movable soft iron armature 85 2. The armature 2 is connected at each end by rods 3 and 4 to vibratory diaphragms 5 and 6. These diaphragms are connected in any desired manner to casings or tubes 7 and 8 which may, in any well known manner not shown, be connected to a horn or amplifying device. The connection between each rod and its diaphragm is, however, owing to the slight inevitable flexibility of 90 the rods and of each diaphragm, not so rigid 95 as to fail to permit the desired vibration of the system. The diaphragm and the rods may be of non-magnetic material. The sound output from the diaphragms is led, as above mentioned, through the similar 100 tubes or casings 7 and 8 to any amplifying or megaphonic device.

The varying electrical current which it is desired to reproduce as sound is passed through the coil 1. Thus the intensity and 105 direction of the polarity of the armature 2 are varied; and, as a result, the armature experiences a twist, since its two ends tend to move in opposite directions in the two constant magnetic fields. On account of the 110 symmetry of the design, the resultant motions of the diaphragms 5 and 6 will be

alike. The ratio of the amplitude of their motion to the amplitude of motion of the armature may be made considerably greater than unity by choosing the desired length for the rods 3 and 4.

It should be understood that gravity plays no part in the operation of this device. Although in Figure 1 the diaphragms are shown as directing their sound outputs along the vertical direction, this is not essential, and the apparatus would operate equally well in any other position.

The sound outputs of the two diaphragms are equal in intensity and phase just before they are made to combine in a horn or magnifying device (not shown), since the casings or tubes 7 and 8 are exactly similar, and the arrangement of the diaphragms 5 and 6 is exactly symmetrical. Thus the total volume of sound obtained with this device corresponds to an amplitude of sound waves in air twice as great as would be excited if the sound output of only one of the diaphragms were led to the said horn. Thus the efficiency of this device, that is the ratio of the total power of the sound output to the electrical power absorbed, is approximately doubled by the utilization of the sound output from two diaphragms.

As regards the feature of this invention which consists in the abolition of the fixed pivot, it is not however, essential that the acoustic output from both diaphragms be utilized. Thus the ear could be applied directly over one of the diaphragms, and in this case it may be desirable to place in front of the other diaphragm a small enclosed chamber designed to imitate the acoustic impedance of the ear, so as to preserve completely the symmetry of the system. Of course, it is not essential that this invention be used as a loud speaker; it may be arranged to be employed as an ordinary telephone receiver.

The essential feature of this invention is the employment of two diaphragms connected to a vibrating armature disposed in a

magnetic field whereby a fixed pivot is eliminated. The receiver contemplated in accordance with this invention offers two advantages over other receivers. First, on account of the absence of a fixed pivot the loss of energy caused by such a pivot is obviated. Even if a pivot is employed with the arrangement described herein, it will introduce but little loss of energy, since the armature and the lever system are supported by the diaphragms. Secondly, the substitution of an additional diaphragm offers in itself the advantageous capability of increasing the amplitude and volume of the sound issuing from the receiver.

What I claim is:

1. In a telephone receiving device, a vibratory armature, a substantially fixed magnetic field disposed transversely across each end of the armature, a coil embracing the middle portion of said armature and adapted to receive speech currents, the magnetic action of the currents in said coil changing the polarity of the ends of the armature, levers extending in opposite directions from the ends of said armature in a line substantially parallel to the axis of the armature, and diaphragms connected to the ends of said levers, said armature being supported from said diaphragms.

2. In a telephone receiving device, a vibratory armature, a substantially fixed magnetic field disposed transversely across each end of the armature, a coil embracing the middle portion of said armature and adapted to receive speech currents, the magnetic action of the currents in said coil changing the polarity of the ends of the armature, levers extending in opposite directions from the ends of said armature in a line substantially parallel to the axis of the armature, the ends of said levers bent respectively in opposite directions at right angles to the axis of the armature, and diaphragms connected to the ends of the levers.

WALTER VAN BRAAM ROBERTS.
